UNITED STATES PATENT OFFICE.

JOHN BALOC, OF HAZLETON, PENNSYLVANIA.

DOOR-OPERATING MECHANISM.

1,348,076.

Specification of Letters Patent. Patented July 27, 1920.

Application filed June 5, 1919. Serial No. 301,901.

To all whom it may concern:

Be it known that I, JOHN BALOC, a citizen of the United States, and a resident of Hazleton, in the county of Luzerne and State of Pennsylvania, have invented a new and Improved Door-Operating Mechanism, of which the following is a full, clear, and exact description.

The object of the invention is to provide a new and improved door operating mechanism more especially designed for opening and closing garage doors and the like, and arranged to open the doors by an incoming or advancing automobile or other vehicle, to keep the doors open until the vehicle has safely passed the doors and finally to close the doors and hold the same in a closed position. Another object is to accomplish the opening and closing of the doors without requiring any attention on the part of the person in charge of the vehicle.

With these and other objects in view, the invention consists of certain novel features of construction, as hereinafter shown and described and then specifically pointed out in the claims.

A practical embodiment of the invention is represented in the accompanying drawings forming a part of this specification, in which similar characters of reference indicate corresponding parts in all the views.

Figure 1 is a sectional plan view of the door operating mechanism as applied to the doors of a garage;

Fig. 2 is a front elevation of the same with parts shown in section;

Fig. 3 is a transverse section of the same on the line 3-3 of Fig. 1;

Fig. 4 is an enlarged sectional front elevation of a portion of the door operating mechanism on the line 4-4 of Fig. 1; and

Fig. 5 is an enlarged sectional plan view of the same on the line 5-5 of Fig. 4.

The door operating mechanism is shown applied to the doors 10 of a garage 11 and the said doors 10 are attached to vertically disposed pintles or shafts 12 by the use of door straps 13. The lower ends of the pintles 12 are journaled in steps 14 and the upper ends of the said pintles are journaled in bearings 15. The steps 14 and the bearings 15 are attached to the sides 16 of the door frame having the usual opening 17 for the passage of an automobile or other vehicle going in or out of the garage.

The lower ends of the pintle 12 are pro-

vided with spiral grooves 20 into which project pins 21 secured to sleeves 22 mounted to slide up and down on the lower ends of the pintles or shafts 12 with a view to turn the said pintles and thereby open and close the doors 10, as hereinafter more fully explained. The sleeves 22 are provided with lugs 25 connected by pivots 26 with arms 27 projecting sidewise from runways 28 extending in openings 29 formed in the roadway or floor 30 leading to the interior of the garage. The runways 28 are connected at their inner ends by hinges 35 and 36 to the middle portion of the floor, as plainly indicated in Fig. 1, and the said runways 28 rest on springs 40 mounted on the framework 41 supporting the floor 30 at the door frame 16, as plainly illustrated in Figs. 1, 3 and 4. Normally the runways 28 are flush with the floor 30 and extend from a distance outside the door opening to a distance within the garage to permit the wheels of an automobile or other vehicle to readily pass over the runways into or out of the garage.

The doors 10 are normally in a closed position and the runways 28 are held in uppermost position by their springs 40. Now when an automobile passes up the runways 28 toward the doors 10 then the weight of the vehicle causes the runways 28 to swing downward and in doing so the arms 27 of the runways move the sleeves 22 downward on the pintles 12 whereby the pins 21 in engagement with the spiral grooves 20 cause the pintles to turn and thereby swing the doors 10 into open position to allow the automobile to pass over the runways 28 into the garage. When the rear wheels of the automobile finally leave the inner ends of the runways 28 then the latter return to their normal uppermost position by the action of the springs 40 and in doing so the sleeves 22 are moved back to uppermost position whereby their pins 21 turn the pintles 12 in a reverse direction thus closing the doors 10. It is understood that when the automobile backs out of the garage and the rear wheels pass onto the inner ends of the runways 28 then the latter swing downward and the doors 10 are opened to allow the automobile to pass out of the garage, and when the front wheels finally leave the outer ends of the runways 28 the doors 10 return to closed position.

From the foregoing it will be seen that by

the arrangement described the person in charge of the automobile or other vehicle is not required to pay any attention to the door operating mechanism.

Having thus described my invention, I claim as new and desire to secure by Letters Patent:-

1. In a door operating mechanism, runways hinged at their longitudinal edges to swing up and down, said runways being of a length to extend across and on each side of the doorway, springs supporting the runways normally in uppermost position, pintles mounted to turn, a door secured to each pintle, and connections between the free edges of the runways and pintles for operating the latter from the runways to open the doors in either direction of travel of a vehicle on the runways.
- 10 2. In a door operating mechanism, a hinged runway adapted to swing upward and downward, said runway being of a

length to extend across the doorway and on each side of the same, a spring for supporting the runway normally in uppermost position, a door, a pintle mounted to turn and on which the door is secured, a member mounted on the lower end of the spindle, and pivotally connected with the runway, and a groove and pin connection between the 30 said member and pintle.

3. In a door operating mechanism, a runway hinged at each end, said runway extending across the doorway and on each side of the same, a spring arranged below and intermediate of the ends of the runway and holding the same normally in uppermost position, a spindle having a spirally grooved lower end and mounted to turn, a door secured to the spindle, a sleeve mounted 40 on the spindle, and having a pin engaging the groove thereof, and an arm on the runway and pivoted to the sleeve.

JOHN BALOC.
